EXTRUSION DIE FOR TUBING

Dalton H. Clark, Pontiac, Mich.

Application October 14, 1948, Serial No. 54,449

3 Claims. (Cl. 207—17)

1

This invention relates to dies and, in particular, to extrusion dies for producing metal tubing.

One object of this invention is to provide a tubing extrusion die which is well adapted for the extrusion of brass and copper tubing, and enabling the removal of the billet butt and its replacement by a fresh billet without substantial interruption in the extrusion procedure.

Another object is to provide a tubing extrusion die which eliminates the necessity for the use of a floating mandrel hitherto used in extruding brass and copper tubing, and which provides a smooth and uninterrupted flow of the metal from the billet to the extrusion ring.

Another object is to provide a tubing extrusion die having multiple portholes converging into an annular mixing chamber around an integral core or mandrel, the latter in turn opening into the annular opening between the extrusion ring and the mandrel.

Another object is to provide a tubing extrusion die of the foregoing character wherein the central portion of the die on its entrance side is rounded so as to direct the metal from the billet into the multiple converging portholes which surround the central portion of the die.

In the drawings:

Figure 1 is a central vertical section through a brass tubing extrusion die as installed in an extrusion press, and with a metal billet engaging the entrance side of the die prior to the commencement of extrusion along the line 1—1 in Figure 3;

Figure 2 is a cross-section along the line 2—2 in Figure 1, showing the entrance side of the extrusion die in front elevation;

Figure 3 is a cross-section along the line 3—3 in Figure 1, showing the exit side of the extrusion die in rear elevation;

Figure 4 is a fragmentary longitudinal section along the line 4—4 in Figure 2;

Figure 5 is a longitudinal section along the line 5—5 in Figure 3; and

Figure 6 is a longitudinal section similar to Figure 1, but showing the apparatus in a later stage of operation wherein a portion of tubing has been extruded.

In the extrusion of brass or copper tubing, it has hitherto been found difficult to extrude the brass or copper without the employment of a floating mandrel which projects outward into the brass or copper billet which furnishes the material for the tubing. These billets are heated to approximately 1350° F. to 1400° F. depending upon the particular alloy. When the billet

2

has been pushed as far as practical into the die, it cannot be removed by pulling it rearwardly. Accordingly, in such extrusion operations as hitherto conducted, the butt remaining from the billet has had to be removed from the die before the operator could start extrusion with a new billet.

The extrusion die of the present invention eliminates the floating mandrel and instead employs a mandrel which is solidly built into the die and does not project from it. The mandrel is surrounded by converging portholes through which the hot metal is forced by the extrusion press. The butt remaining from the billet is capable of removal merely by pulling it out after the maximum amount of material has been extruded. In removing the butt by pulling it out of the die, the die is not injured since the stems or streams of metal remaining within the converging portholes are fractured as the butt is pulled out. A new billet, suitably heated, can then be immediately placed against the die and extrusion recommenced without loss of time. The die of the present invention has smoothly converging portholes and passageways leading to the extrusion ring, without substantial shoulders or abutments which would impede the flow of the metal. As a consequence, metal tubing is quickly and efficiently extruded and tubing having unusually thin walls can be extruded and extrusion can be almost continuously carried out, with but slight halts necessitated by the withdrawal of the butt and the insertion of a new billet. The die, by reason of its novel construction, contains a minimum amount of hot metal which flows freely through the portholes into the mixing chamber and thence through the annular extrusion opening between the extrusion ring and the mandrel.

Referring to the drawings in detail, Figure 1 shows a portion of an extrusion press, generally designated 10, in which is inserted a tubing extrusion die, generally designated 11, according to the present invention, by which tubing is extruded from brass or copper billets B. The extrusion press 10 is of conventional design, its details forming no part of the present invention, and any suitable conventional extrusion press may be used. For the purposes of the present disclosure, it is shown as including a cylinder 12 having a cylinder bore 14 in which the metal billet B is inserted and engaged by a plunger or ram (not shown). The forward end of the cylinder 12 rests against an abutment member 13 which, in turn, rests against the die housing 15.

connected to the bed (not shown) of the extrusion press. The die housing 15 is provided with a counterbore 16 terminating in an annularly shouldered rear or bottom surface 17 having a central opening or bore 18 through which the completed tubing emerges. The abutment member 13 is also provided with an opening or bore 19 of slightly smaller diameter than the bore 16, so as to retain the die 11 in position.

The die 11 consists generally of a die body 20 and an extrusion ring 21 inserted in a counterbore or recess 22 in the rearward end of the body 20 and having a bottom or rear surface 23. The body 20 is surrounded by an annular groove 24 which receives the abutment member 13 (Figure 1) and is held in position by the latter. The die body 20 is of generally cylindrical shape with a slightly recessed front surface 25 and a flat rear surface 26, the latter abutting the annular shoulder 17. In the center of the front surface 25 is a slightly rounded protuberance 27 surrounded by a dished portion 28 in which are located inwardly and rearwardly converging portholes or metal passageways 29 having flared entrance portions 30.

The portholes 29 are arranged on opposite sides of a central integral core 31 forming a mandril and having an extension 32 extending rearwardly (Figures 1, 4 and 5). The mandril portion 32 is surrounded by a neck portion 33 which is of slightly reduced diameter and which separates it from the main portion of the core 31 and which forms part of the wall of an annular mixing chamber 34 into which the portholes 29 converge (Figures 1 and 4). The portholes 29 are separated from one another by web portions 35 and have the rearward outlets 36 opening into the mixing chamber 34.

Beyond the mixing chamber 34 the mandril or core extension 32 is provided with an approximately cylindrical outer surface 37 which is spaced radially from the corresponding surface of the bore 38 in the extrusion ring 21 so as to form an annular extrusion passageway 39 therebetween. The extreme end 40 of the mandril or core extension 32 is slightly rounded or bevelled and the corresponding end portion 41 of the extrusion ring bore 38 is flared outwardly. The central portion 42 of the extrusion ring surface or bore 38 is cylindrical and the inner portion 43 approximately conical, converging toward the cylindrical portion 42 in a continuation of the converging direction of the portholes or metal passages 29. The front or inner edge 44 of the bore 38 in the extrusion ring 21 is rounded to prevent the formation of a shearing edge and to enhance the flow of the metal from the mixing chamber 34 into the passageway 39.

In order to properly locate the extrusion ring 21 in its recess or counterbore 22, the ring 21 is provided with a hole 45 (Figure 5) with which is aligned a corresponding hole 45a in the die body 20. The hole 45 receives a dowel pin or locating pin 46 which enters the locating hole 45a when the ring 21 is properly inserted in its recess 22 in the die body 20. The mandril portion 32 of the die body 20 and the extrusion ring 21 thus form male and female dies respectively, between which the metal is extruded from the billet B to form a tube T (Figure 6).

Operation

In the operation of the invention a suitably heated metal billet B is placed in the bore 14 of the cylinder 12 and pressure applied by the

usual plunger (not shown) to force the inner end of the billet B against the forward end 25 of the die body 20. The metal first encounters the rounded protuberance 27 which projects like an island from the center of the dished portion 28. The protuberance 27 and the flared entrances 30 assist in diverting and facilitating the flow of the metal into the converging portholes 29 and thence into the mixing chamber 34. The streams of metal flowing through the portholes 29 reunite in the mixing chamber 34 where they are caused to intermingle by the slight back pressure set up by the fact that the annular extrusion passageway 39 is somewhat narrower than the mixing chamber 34 (Figures 1 and 5). The metal, thus thoroughly mixed and intermingled, flows out through the extrusion passageway 39 and forms the tube T which is then handled in the usual way.

When as much of the billet B has been extruded as is conveniently practical and it is necessary to change billets, the removal of the butt of the billet B is easily accomplished merely by grasping it and forcibly pulling it backward away from the extrusion die 11, or conversely, by pulling the die from the billet. When this is done, the stems S (Figure 6) remaining in the portholes 29 are ruptured without harm, severing the butt from the extruded tube T. It is then merely necessary to withdraw the butt of the billet B and insert a new heated billet B, apply pressure thereto by means of the plunger or ram of the extrusion press 10 and continue operations with very little interruption. This procedure, which is made possible by the construction of the extrusion die 11 of the present invention, avoids the time consuming procedure previously necessary in removing the butt where a floating mandril was used in connection with the extrusion die in extruding brass or copper tubing.

In the present invention, the mandril extension 32 and the core 31 are integral with the die body 20, hence no injury to them can occur by the withdrawal of the butt, whereas the forcible withdrawal of the billet butt from prior dies employing floating mandrels has not been feasible. Since the portholes 29 converge smoothly without abrupt shoulders or abutments toward the extrusion passageway 39, the metal flows smoothly and uninterrupted and is free from shearing edges.

The extrusion die of the present invention provides a mixing chamber 34 which tends to impart a circular motion to the streams of metal thus creating an improved intermingling and bond between them. This circular motion is enhanced by the contour of the outlets 36 of the portholes 29. The mandril portion 32 and extrusion ring 21 enhance this circular motion. The number of portholes may be increased or decreased, depending upon the size and shape of the tube desired. The converging arrangement of the portholes 29 tends to give greater strength to the core 31, including the mandril portion 32 and also facilitates pulling away the billet butt when it is necessary to change billets. The flared portion 41 at the outlet of the extrusion ring 21 enables the metal to flow over it rather than be sheared as in the action with certain types of aluminum extrusion dies. This shearing action is detrimental in extruding brass or copper tubing.

The portholes 29 are preferably equally spaced around the core or mandril 31 and accurately drilled to provide equal pressure on all sides of

the mandril. The size of the portholes is determined by the size of tube and wall thickness required, and also by the necessity of providing sufficient support for the mandril. The front face 25 of the die body 20 is concave or dished as at 28 to permit the front end of the billet B to fit more snugly so as to prevent spreading of the butt. The formation of the mandril or core 32 is an integral part of the die body 20, together with the relatively small diameters of the portholes 29 and their converging arrangement permits the billet butt to be pulled off cleanly and a new billet to be inserted immediately without substantial interruption.

The extrusion die 11 of the present invention is adapted to be used in almost any type of extrusion press which is available on the market. The configuration of the extrusion ring bore 38 and mandril extension 32 may be varied to suitably shape the passageways 39 so that tubing of any desired cross-sectional shape may be extruded; for example, tubing of round, oval, square, hexagonal or octagonal cross-section. It will be understood that the extrusion of copper requires a higher temperature for the billet than brass. Accordingly, a grade of steel or other suitable metal which will withstand the higher temperature must be used for the parts of the die which come into contact with the hot copper. Such steel capable of withstanding a higher temperature required for extruding the copper tubing is available on the market.

What I claim is:

1. A die for extruding brass or copper tubing comprising a die body having metal flow passageways converging inwardly and rearwardly from the forward portion thereof, a mixing chamber interconnecting said passageways, and an approximately annular extrusion opening communicating with said mixing chamber, the major portion of the forward face of said die body having a raised peripheral portion projecting forwardly therefrom and a concave surface disposed inwardly of said peripheral portion and depressed

below the level thereof, the entrances to said flow passageways being located in said concave surface.

2. A die for extruding brass or copper tubing comprising a die body having metal flow passageways converging inwardly and rearwardly from the forward portion thereof, a mixing chamber interconnecting said passageways, and an approximately annular extrusion opening communicating with said mixing chamber, the major portion of the forward face of said die body having a concave surface, the central part only of said concave surface having an approximately central protuberance therein and the entrances to said flow passageways being located in said concave surface laterally outward of said protuberance.
3. A die for extruding brass or copper tubing comprising a die body having metal flow passageways converging inwardly and rearwardly from the forward portion thereof, a mixing chamber interconnecting said passageways, and an approximately annular extrusion opening communicating with said mixing chamber, the major portion of the forward face of said die body having a concave surface, the central part only of said concave surface having an approximately central protuberance therein and the entrances to said flow passageways being located in said concave surface adjacent to and laterally outward of said protuberance.
